US0D1027200S

(12) **United States Design Patent** (10) **Patent No.:** **US D1,027,200 S**
(45) **Date of Patent:** **** May 14, 2024**

(54) **CRYOGENIC DEVICE**

(71) Applicant: **Pacira CryoTech, Inc.**, Parsippany, NJ (US)

(72) Inventors: **Jeffrey N. Gamelsky**, Palo Alto, CA (US); **Pierre-Andre Mugnier**, Moss Beach, CA (US); **Eric T. Johansson**, Dublin, CA (US); **Andrew Huffmaster**, Fremont, CA (US)

(73) Assignee: **Pacira CryoTech, Inc.**, Tampa, FL (US)

(**) Term: **15 Years**

(21) Appl. No.: **29/896,005**

(22) Filed: **Jun. 28, 2023**

Related U.S. Application Data

(63) Continuation of application No. 29/780,705, filed on Apr. 26, 2021, now Pat. No. Des. 995,802.

(57) **CLAIM**

The ornamental design for a cryogenic device, as shown and described.

DESCRIPTION

FIG. 1 is a front isometric view of a cryogenic device.

FIG. 2 is a back isometric view of the device of FIG. 1.

FIG. 3 is a front view of the device of FIG. 1.

FIG. 4 is a back view of the device of FIG. 1.

FIG. 5 is a left side view of the device of FIG. 1.

FIG. 6 is a right side view of the device of FIG. 1.

FIG. 7 is a top view of the device of FIG. 1; and,

FIG. 8 is a bottom view of the device of FIG. 1.

The broken lines indicate unclaimed portions of the cryogenic device that form no part of the claimed design.

1 Claim, 7 Drawing Sheets
